TACK BUTTON

Edmund D. Janes, Waterbury, Conn., assignor to
 Scovill Manufacturing Company, Waterbury,
 Conn., a corporation of Connecticut

Application December 22, 1944, Serial No. 569,661

16 Claims. (Cl. 24—95)

1

This invention relates to fastening devices generally referred to as tack buttons. More particularly, the invention deals with devices of this kind employing a more or less standard construction in the blank of the button body, adapting the button body to the attachment of different types of heads in forming closed and open heads on the resulting button, and further in adapting said body for the reception of tack engaging members of different constructions and retained against displacement from the button body by suitably shaping the shank portion of said body. Still more particularly, the invention relates to the use of tack coupling members having wall portions extending longitudinally of the walls of the button shank to minimize the turning or heading of the pointed end of a tack and also in insuring a more positive and firm mounting of the button in connection with a support. The novel features of the invention will be best understood from the following description when taken together with the accompanying drawing, in which certain embodiments of the invention are disclosed, and in which the separate parts are designated by suitable reference characters in each of the views, and in which:

Fig. 1 is a sectional view through one form of button which I employ illustrating the same secured to a support by attachment of a tack.

Fig. 2 is a view similar to Fig. 1, showing the button prior to attachment of a tack therewith.

Fig. 3 is a view similar to Fig. 1, showing an open head on the button.

Figs. 4 to 7 inclusive are views similar to Fig. 2, showing other forms of construction; and

Fig. 8 is a sectional view through the body portion of a button, showing another modification.

With buttons of the type under consideration, there have been difficulties experienced in firmly securing the buttons to supports and in maintaining proper alinement of the buttons on the supports. These difficulties have been largely due to the necessity of excessively turning over or heading the tack to securely attach the button to the support, which has brought about distortion of the button on the support and also resulted in a looseness in mounting due to displacement or shifting of the button parts.

These objectionable features I have overcome by providing relatively long tack engaging members or sleeves which may also be termed anvils, which minimize the amount of turning over or heading of the tack in securing the button to the tack and the support. Further by pre-fixing and positively retaining these members or coupling

2

sleeves in the button body, a positive and non-shifting attachment of the button to the support is provided. A relatively large base or end is provided on the button shank between which and the button head the support is adapted to be clamped in such manner as to form a better alinement of the button and tack one with respect to the other, and thus a proper mounting on the support. Still further, the coupling member or sleeve is reinforced to withstand the pressure applied to the tack end in turning or heading the same, and in this connection, the member or sleeve has substantially perpendicular wall portions which parallel the axis of the tack, thus further aiding in maintaining the alinement of the parts in attachment to a support.

Another distinctive feature of my invention resides in the use of what might be termed a button body blank formed to the point of attachment of the tack engaging member or sleeve, which will be universally adaptable for the reception of members or sleeves of different contour as well as to adapt the button for attachment of closed or open heads. Further, the size of the shank may be standardized to fit the coupling or fastener devices adapted to engage the button.

In Figs. 1 and 2 of the drawing, I have shown one form of button comprising a body part 10, 30 consisting of a tubular shank portion 11, one end of which terminates in an outwardly extending integral annular flange or head 12 forming part of the head of the resulting button. The flange has an outwardly turned rim 13 adapted to be engaged by an inwardly turned rim 14 on the button top or cover 15. The top or cover 15 is in the form of a closed disc, as seen in Figs. 1 and 2, and between the top 15 and the flange 12 is arranged a filler or anvil plate 16.

40 The other end of the shank 11 has an inwardly extending and slightly annular flange 17 which forms the bottom wall of the button and this wall has a central opening 18 to freely receive the prong 19 of a tack 20. The head 21 45 of the tack 20 is of a diameter substantially the same as the diameter of the bottom wall 17 of the shank 11, or in other words, the diameter of said shank. It will thus be seen that in securing the button to a support 22, a gripping engagement is established between the large diameter of the head 21 and the button shank.

Arranged within the shank 11 is a tack engaging or coupling member or sleeve 23 or the tubular portion thereof. The sleeve 23 extends 55 a substantial length of the shank so as to dis-

pose the inturned upper or flanged end 24 of the sleeve adjacent the plate 16. The flange 24 forms a reduced opening 25 in the inner end of the sleeve through which the pronged end of the tack 29 is adapted to pass in the operation of turning or heading this end, as seen at 26 in securing the button in position on the support 22.

The lower end of the sleeve 23 has an outwardly extending and slightly conical annular flange 27 which is adapted to seat upon the inner surface of the wall 17. In assembling the parts 10 and 23, prior to attachment of the plate 16 and cap 15 to the part 10, the shank will have a straight perpendicular wall which will facilitate free insertion of the part 23 into the shank portion 11 of the part 10. After being inserted into position, the wall of the shank 11 is forced inwardly to provide an annular bead or indenture 28 closely adjacent the flange 27 to overlap said flange and securely support it upon the wall 17. In this way, the sleeve 23 becomes securely fixed in the button body 10. In addition to securing the sleeve 23 in position, the circumferential indenture or inwardly formed bead 28 also provides a means reinforcing and strengthening the shank portion 11. After the sleeve 23 has been secured in position, the resulting button blank is provided, and to this blank may be attached any type or kind of cap construction, such as the cap 15 of Fig. 1, or a cap such as later described in connection with Fig. 3, could also be employed. This is also desirable from the standpoint of applying finishing caps of different design and contour suitable to the tastes of the customer to whom the buttons are supplied. It will here also be apparent that the finishing caps may be composed of metal or plastic materials to further give design as well as color to the resulting button.

In Fig. 3 of the drawing is shown a slight modification, and as the parts 10 and 23 are identical to the corresponding parts shown in Figs. 1 and 2, like references will represent like parts in Fig. 3. In this figure, I have substituted for the cap 15, a cap 29 which has an inturned rim portion 30 fitting the rim 13 of the flange 12. The cap 29 is in the form of a ring like body, and the bore of this body has an inturned annular hub portion 31 which forms a large opening 32, substantially of the same diameter as the bore of the shank 11. This produces what is commonly referred to as an open head button, which facilitates turning or heading the end of the prong 33 of a tack 34 in the manner indicated at 35. The tack 33 includes a head 36 which is also substantially of the same diameter as the diameter of the bottom wall 17 of the button body or the shank 11 thereof.

In Fig. 4 is shown at 37 another form of button employing a body 38 substantially of the same general form as the body 10, particularly when in its blank contour and prior to attachment of the coupling member or sleeve 39 therewith. The primary difference in the structure shown in Fig. 4, from that shown in Figs. 1 and 3, is in the form of the sleeve 39 and the manner of securing the sleeve in position in the button body. The sleeve terminates at its upper or inner end in an inturned reinforcing flange 40 defining a restricted opening 41 at said end of the sleeve, similar to the opening 25. The other end of the sleeve has an outwardly extending flange 42 which seats upon the inturned and

slightly conical annular wall 43 of the button body and similar to the wall 17. The flange 42 terminates at its periphery in an upwardly and inwardly curled rim portion 44 which reinforces and stiffens the flange portion of the sleeve. In securing the sleeve 39 in the button body, the shank 45 of the button body is pressed inwardly at a number of circumferentially spaced intervals to form retaining beads 46 which overlie the inturned rim 45, and thus securely supports the sleeve 39 in the button body and retains the same against displacement therefrom.

In Fig. 5 of the drawing is shown a slight modification of the structure shown in Fig. 4, and as the button body 38 is substantially identical to that shown in Fig. 4, like references will designate like parts in Fig. 5. In Fig. 5, the member or sleeve 47 is employed having an upper or inner inturned flange 48, similar to the flange 40, forming a restricted opening 49. The sleeve 47 also includes an outwardly extending annular bottom flange 50, similar to the flange 42, but instead of including upwardly and inwardly turned rims, such as the rim 44, the sleeve 47 simply has an upwardly extending annular rim 51.

In Fig. 6 of the drawing is shown another adaptation of my invention in which a button body 52 is employed which differs from the button body 38 primarily in the location of the inward indentures or beads 53, the latter being shown in closer proximity to the bottom wall 54 and illustrated in Figs. 4 and 5 so as to engage the bottom flange 55 of a coupling member or sleeve 56, the flange 55 being similar to the flange 17. In this connection it will be understood that the sleeve 56 may be secured in position with an annular indenture or bead such as the bead 28, if desired, and in like manner, the localized beads or indentures, such as 53 can be employed in the structure as shown in Figs. 1 and 2. The sleeve 56 differs from the sleeve 23 by having at the upper or inner end thereof an outwardly extending annular flange 57, the periphery of which is arranged in close proximity to the bore 58 of the shank 59, thus supporting and reinforcing the upper inner end of the sleeve against displacement within the shank in the operation of turning or heading the pronged end 50 of the tack. The flange 57 joins the body portion of the sleeve 56 in an inwardly extending circumferential rounded bead portion 60 which forms a restricted opening 61 at the inner end of the sleeve 56, similar to the opening 25.

In Fig. 7 is shown another form of construction in which the button body 52 is identical with the body shown in Fig. 2, thus like references will indicate like parts in Fig. 7. In the latter figure, a coupling sleeve 62 is employed, which differs from the sleeve 56 in providing an outward annular bulge in the central portion of the sleeve, which will provide at upper and lower ends of the bore, restricted openings 63 and 64 and said ends of the sleeves include outwardly extending annular flanges 65 and 66, both of which are slightly conical in form so as to adapt the sleeve 62 for mounting in the button body with either end downward to seat upon the conical bottom wall 54. This will simplify assemblage of the parts. In this connection, it will be apparent that the restricted openings 63 and 64 will be of like diameter and sufficiently large to clear the prong of the tack employed, particularly at the greatest diameter thereof adjacent the head of the tack, as will be apparent from

a consideration of the tack illustration in Figs. 1 and 3 of the drawing. With the construction of Fig. 7, it will be apparent that the flanges 65 and 66, which is uppermost or innermost, such as the flange 65 shown in said figure, will also operate similar to the flange 57 in maintaining the sleeve 62 against tilting movement in the button body.

In Fig. 8 I have shown a button body 61, again generally of the structure shown in the other figures, but the body is shown before attachment of the cap thereto. The structure of Fig. 8 differs from the teachings in the other figures primarily in setting the wall portion or shank 68 of the button body inwardly after arrangement of the member or sleeve 69 upon the annular and substantially conical bottom wall portion 70 of the body 67. In setting the wall 68 inwardly, the lower end portion of this wall is beaded or curled around the outwardly extending annular flange 71 of the sleeve 69, as seen at 72. While the sleeve 69 is of the same general appearance as the sleeve 23, this sleeve may be made of a larger size so that in the final reduction of the shank 68, this shank may be of the same diameter as the shanks shown in the other figures, or of a smaller diameter, particularly when the button is adapted for uses where smaller diameters would be desirable. The upper or inner end of the sleeve 69 has the inturned flange 73 which forms the restricted opening 74 for the reception of the prong of the tack or similar fastener.

In the several forms of construction shown, the sleeves for their inner or upper ends terminate adjacent but inwardly of the flanged head portions of the button bodies, thus adapting all of the button bodies for attachment of caps of the type and kind shown in Fig. 1, for example, as well as those of the kind shown in Fig. 3. It will also be apparent that while attaching members in the form of tacks are illustrated and referred to, any type or kind of attaching members can be employed.

In all of the constructions shown, it will be apparent that the shank of the button includes substantially long wall portions which are parallel to the axis of the button, and the tack engaging member or sleeve includes wall portions which for the most part are also parallel to the axis and spaced from the wall portion of the button shank. These sleeves also include at their inner ends means reinforcing and strengthening the sleeves and at the same time providing restricted openings therein to maintain a close proximity to the prong of the tack, thus maintaining the prong in centralized position within the button body, and further providing a surface upon which the pointed end of the tack prong can be turned or headed. Still further, it will be apparent that by providing long tack engaging sleeves, the extent of turning or heading of the tack is minimized and at the same time, a secure and positive coupling of the parts is maintained.

Having fully described my invention, what I claim as new and desire to secure as Letters Patent is:

1. A tack button comprising a tubular body having an outwardly extending annular head at the upper end, an inwardly extending annular wall at the lower end, a sleeve arranged within said body, said sleeve having an annular flange at its lower end extending outwardly beyond the diameter limits of said sleeve and adapted to seat upon the wall at the lower end of said body, means formed from the material of said tubular

body engaging the flange of said sleeve for securing the sleeve against displacement from said body, and the upper end of said sleeve being flanged and terminating inwardly of the upper head end of said body.

2. A tack button comprising a tubular body having an outwardly extending annular head at the upper end, an inwardly extending annular wall at the lower end, a sleeve arranged within 10 said body, said sleeve having an annular flange at its lower end extending outwardly beyond the diameter limits of said sleeve and adapted to seat upon the wall at the lower end of said body, means formed from the material of said tubular

15 body engaging the flange of said sleeve for securing the sleeve against displacement from said body, the upper end of said sleeve being flanged and terminating inwardly of the upper head end of said body, and the upper end of said sleeve having a restricted opening.

3. A tack button comprising a tubular body having an outwardly extending annular head at the upper end, an inwardly extending annular wall at the lower end, a sleeve arranged within 20 said body, said sleeve having an annular flange at its lower end extending outwardly beyond the diameter limits of said sleeve and adapted to seat upon the wall at the lower end of said body, means formed from the material of said tubular body

25 engaging the flange of said sleeve for securing the sleeve against displacement from said body, the upper end of said sleeve being flanged and terminating inwardly of the upper head end of said body, the upper end of said sleeve having a 30 restricted opening, and the flange at the upper end of said sleeve extending inwardly in forming said restricted opening.

4. A tack button comprising a tubular body having an outwardly extending annular head at 40 the upper end, an inwardly extending annular wall at the lower end, a sleeve arranged within said body, said sleeve having an annular flange at its lower end extending outwardly beyond the diameter limits of said sleeve and adapted to seat 45 upon the wall at the lower end of said body, means formed from the material of said tubular body engaging the flange of said sleeve for securing the sleeve against displacement from said body, the upper end of said sleeve being flanged 50 and terminating inwardly of the upper head end of said body, the upper end of said sleeve having a restricted opening, and the flange at the upper end of said sleeve extending outwardly.

5. A tack button comprising a tubular body 55 having an outwardly extending annular head at the upper end, an inwardly extending annular wall at the lower end, a sleeve arranged within said body, said sleeve having an annular flange at its lower end extending outwardly beyond the diameter limits of said sleeve and adapted to seat 60 upon the wall at the lower end of said body, means formed from the material of said tubular body engaging the flange of said sleeve for securing the sleeve against displacement from said

65 body, the upper end of said sleeve terminating adjacent but inwardly of the head end of said body, and said end of the sleeve having radially extending means arranged in close proximity to the wall of said tubular body.

6. A tack button comprising a tubular body having an outwardly extending annular head at the upper end, an inwardly extending annular wall at the lower end, a sleeve arranged within 70 said body, said sleeve having an annular flange at its lower end extending outwardly beyond the

diameter limits of said sleeve and adapted to seat upon the wall at the lower end of said body, means formed from the material of said tubular body engaging the flange of said sleeve for securing the sleeve against displacement from said body, the upper end of said sleeve terminating adjacent but inwardly of the head end of said body, said end of the sleeve having radially extending means arranged in close proximity to the wall of said tubular body, and means forming a restricted opening at the upper end of said sleeve.

7. A tack button comprising a tubular body having an outwardly extending annular head at the upper end, an inwardly extending annular wall at the lower end, a sleeve arranged within said body, said sleeve having an annular flange at its lower end extending outwardly beyond the diameter limits of said sleeve and adapted to seat upon the wall at the lower end of said body, means formed from the material of said tubular body engaging the flange of said sleeve for securing the sleeve against displacement from said body, and means reinforcing the upper end of said sleeve and forming a restricted opening at said end.

8. A tack button comprising a tubular body having an outwardly extending annular head at the upper end, an inwardly extending annular wall at the lower end, a sleeve arranged within said body, said sleeve having an annular flange at its lower end extending outwardly beyond the diameter limits of said sleeve and adapted to seat upon the wall at the lower end of said body, means formed from the material of said tubular body engaging the flange of said sleeve for securing the sleeve against displacement from said body, means reinforcing the upper end of said sleeve and forming a restricted opening at said end, and the flange of said sleeve including an offset outer rim portion.

9. In buttons of the class described, a button body, said body comprising a tubular shank having an outwardly extending integral head at one end, an inwardly extending wall at the other end with a central aperture therein, a member independent of said body and arranged within said shank, means on said member and shank for retaining said member against displacement from the button body, said member having a tubular portion extending longitudinally of and in axial alignment with the shank of said body and spaced therefrom, the upper end of said member terminating short of the head end of said body, and means at the upper end of said member for reinforcing said end and forming a restricted opening therein.

10. In buttons of the class described, a button body, said body comprising a tubular shank having an outwardly extending integral head at one end, an inwardly extending wall at the other end with a central aperture therein, a member independent of said body and arranged within said shank, means on said member and shank for retaining said member against displacement from the button body, said member having a tubular portion extending longitudinally of and in axial alignment with the shank of said body and spaced therefrom, the upper end of said member terminating short of the head end of said body, means at the upper end of said member for reinforcing said end and forming a restricted opening therein and said last named means including radially extending means arranged in close proximity to the wall of said shank.

11. In buttons of the class described, a button

body, said body comprising a tubular shank having an outwardly extending integral head at one end, an inwardly extending wall at the other end with a central aperture therein, a member independent of said body and arranged within said shank, said member having a tubular portion spaced from said shank, the lower end of the tubular portion of said member having radial means abutting the bottom wall of said body and extending outwardly to the wall of said shank, inwardly extending means on the shank engaging said last named means to support said member firmly in said body, and means for reinforcing the upper end of said member.

12. In buttons of the class described, a button body, said body comprising a tubular shank having an outwardly extending integral head at one end, an inwardly extending wall at the other end with a central aperture therein, a member independent of said body and arranged within said shank, said member having a tubular portion spaced from said shank, the lower end of the tubular portion of said member having radial means abutting the bottom wall of said body and extending outwardly to the wall of said shank, inwardly extending means on the shank engaging said last named means to support said member firmly in said body, means for reinforcing the upper end of said member and forming a restricted opening at said end of the member, the bottom wall of said body being substantially conical in form, and a cap secured to the upper head end of said member.

13. In buttons of the class described, a button body, said body comprising a tubular shank having an outwardly extending integral head at one end, an inwardly extending wall at the other end with a central aperture therein, a member independent of said body and arranged within said shank, said member having a tubular portion spaced from said shank, the lower end of the tubular portion of said member having radial means abutting the bottom wall of said body and extending outwardly to the wall of said shank, inwardly extending means on the shank engaging said last named means to support said member firmly in said body, means for reinforcing the upper end of said member and forming a restricted opening at said end of the member, the bottom wall of said body being substantially conical in form, a cap secured to the upper head end of said member, and an anvil plate between said cap and head end of the body and arranged over said member.

14. In buttons of the class described, a button body, said body comprising a tubular shank having an outwardly extending integral head at one end, an inwardly extending wall at the other end with a central aperture therein, a member independent of said body and arranged within said shank, said member having a tubular portion spaced from said shank, the lower end of the tubular portion of said member having radial means abutting the bottom wall of said body and extending outwardly to the wall of said shank, inwardly extending means on the shank engaging said last named means to support said member firmly in said body, said last named means comprising an inwardly set annular wall portion on said body, and means forming a restricted opening at the upper end of said member.

15. In buttons of the class described comprising a button body part and an independent attaching member engaging part, said member engaging part being adapted to be secured in said body and

comprising a sleeve, upper and lower ends of the sleeve being flanged, the flange at the upper end of the sleeve forming a restricted opening at said end thereof, and the flange at the lower end of the sleeve extending outwardly and being substantially conical in form.

16. In buttons of the class described comprising a button body part and an independent attaching member engaging part, said member engaging part being adapted to be secured in said body and comprising a sleeve, upper and lower ends of the sleeve being flanged, the flange at the upper end of the sleeve forming a restricted opening at said end thereof, the flange at the lower end of the sleeve extending outwardly and

5

being substantially conical in form, and said last named flange having an offset rim portion.
